UNITED STATES PATENT OFFICE.

HALBERT B. HALVORSEN, OF CHICAGO, ILLINOIS, ASSIGNOR TO SULLIVAN MACHINERY COMPANY, A CORPORATION OF MASSACHUSETTS.

COMPRESSOR-UNLOADING MECHANISM.

1,401,944.

Specification of Letters Patent. Patented Dec. 27, 1921.

Application filed April 22, 1919. Serial No. 291,819.

To all whom it may concern:

Be it known that I, HALBERT B. HALVORSEN, a citizen of the United States, residing at Chicago, in the county of Cook and State 5 of Illinois, have invented certain new and useful Improvements in Compressor - Unloading Mechanism, of which the following is a full, clear, and exact specification.

My invention relates to compressors and 10 more particularly to a compressor unloading means.

In the operation of a multi-stage compressor, it is a common practice to provide unloading means for the lowest stage cylinder 15 of a compressor in order to render this stage inoperative when the pressure in a receiver or a pipe line rises above normal operating pressure. When this cylinder is unloaded, that is, when it is not operating to compress 20 air, there is apt to be a slight leakage through the cylinder to the second stage cylinder of the compressor and this air which leaks through the first cylinder will be compressed in the second cylinder from about 25 atmospheric pressure to a relatively high pressure with a resultant much greater rise in the temperature. For example, if a two-stage compressor is used to compress air to 100 pounds and an intercooler is used between 30 the stages of the compressor, the final temperature of the compressed air will be about 243° F., if the air were compressed from about atmospheric pressure to 100 pounds pressure in the second stage only, the 35 temperature would rise to about 485° F. This high temperature might under some conditions be sufficient to explode combustible mixtures of oil and air which occur in the cylinders, due to the vaporization of the 40 lubricating oil which is usually injected into the cylinders with the air to be compressed.

One object of the present invention is to provide an improved compressor unloading means especially applicable to one of the 45 high stages of a multi-stage compressor for unloading this stage to prevent excessive temperatures therein and especially to prevent overheating when the lower stage is unloaded. Another object of the present invention is to provide an improved and simple unloading means which may easily be applied to any compressor and which is composed of a very few parts which are easily assembled and in which the wear is 50 reduced to a minimum. These and other ob-

jects and advantages of my improvement will, however, hereafter more fully appear.

In the accompanying drawings, I have shown for purposes of illustration, one embodiment which my invention may assume 60 in practice.

In these drawings,—

Figure 1 is a side elevation of a two-stage compressor provided with my improved unloading means.

Fig. 2 is a longitudinal sectional view 65 through the unloading means.

In this illustrative construction, I have shown my invention applied to the high pressure cylinder of a two-stage compressor having a low pressure cylinder 1 and a high pressure cylinder 2 connected in a well known manner by an intercooler 3, these parts being preferably mounted upon a base 4. The air or other fluid to be compressed 70 is drawn in through an inlet 5 having therein an unloading means 5' which may be of any of a number of well known types, the air entering the low pressure cylinder through inlet valves 6 and being forced 80 from this cylinder into the intercooler 3 through discharge valves 7, these valves being preferably of the automatic spring operated type, although if desired any other type of valve may be used. The air compressed in the primary cylinder 1 is first 85 cooled in the intercooler 3 and is then drawn into the high pressure cylinder 2 through the inlet valves 8, and after being compressed in this cylinder, it is forced out into a pipe line 9' connected to a receiver, not necessary to show herein, through outlet valves 9 which may if desired be of the same type as the valves on the primary cylinder. 90

I preferably provide a plurality of high pressure cylinder unloading means 10 communicating with an exhaust passage 11 and mount the unloading means adjacent the opposite ends of the high pressure cylinder and 100 preferably in communication with the interior of the cylinder itself. Referring more particularly to Fig. 2, it will be seen that my unloading means is connected with the interior of the cylinder by means of a short 105 pipe 12, which conducts the pressure fluid from the interior of the cylinder to an annular space 13 in the casing 14 of the unloading mechanism 10 and that the compressed air or other fluid in the pipe line 12 and annu- 110

lar space 13 will be exhausted through the longitudinal passageway 15 to the exhaust pipe 11 when these passages are placed in communication by proper valve mechanism.

5 It will be understood that the pipe 12 communicates with the compression space of the cylinder 2 at such point as to subject the thermostatic control means to the highest temperatures produced during compression.

10 In the form of my improvement shown herein, this valve mechanism comprises a valve stem 16 herein shown as hollow, carrying on one end thereof a valve head 17 adapted to seat against the valve seat 18 to close communication between the passages 13 and 15.

15 I have also provided a valve stem guiding means herein shown in the form of fins or wings 19 carried by the valve stem in engagement with the casing 14, but as is obvious, these wings may be formed on the casing and engage the valve stem 16 to guide the latter. The valve stem 16 and the casing 14 are preferably formed of different materials having different coefficients of heat ex-

25 pansion, the stem 16 preferably having the lower coefficient of expansion and the wings 19 are so formed that the fluid compressed in the cylinders and forced into the valve casing 14 will flow into the space between the 30 valve stem 16 and the casing 14 so that this stem and casing will be subjected to the heat variations within the cylinder. The stem and casing having different coefficients of heat expansion will expand unequally and 35 since the member 16 has the lowest coefficient of expansion, the casing 14 will be elongated to a greater extent as the temperature rises and the head 17 will be drawn away from the seat 18 permitting the exhausting of the 40 high pressure cylinder through pipe 12, annular space 13, and passageway 15 to the exhaust pipe 11 thereby reducing the pressure and the temperature in the high pressure cylinder.

45 Since the contraction of the casing 14 during a decrease of temperature may force the valve head 17 against the valve seat 18 with a pressure sufficient to injure some of the valve mechanism, I preferably provide a lost 50 motion connection between the valve stem 16 and the valve casing 14. In the form of my improvement shown herein, this lost motion connection consists of a valve rod 20 having threaded connection as shown at 21 with the 55 valve stem 16 and passing centrally through a guiding and adjusting plug 22 in the end of the casing 13, the outer end of the valve rod 20 preferably being threaded as shown at 23 to receive a nut 24 which engages the 60 adjusting plug 22. A spring 25 is also preferably provided to normally seat the valve head against the valve seat 18, but if the casing 14 should contract to such an extent as to 65 tend to force the valve head against the seat with an undue pressure, the valve spring

25 will be compressed and thereby relieve the valve mechanism of any excessive strain. As is apparent, the valve stem may be adjusted in relation to the valve casing 14 through a movement of the plug 22 with relation to the casing 14 or of the nut 24 on the threaded end 23 of the valve rod 20, thereby permitting an adjusting of the spring tension and an adjustment in the movement of the valve stem 16.

70 Since there is a wide range of variation between the temperatures generated in the first stage of a multi-stage compressor, and in the final stage of a multi-stage compressor when the latter is operating to compress air 80 from atmospheric pressure to final pressure, the thermostatic unloading mechanism may easily be set to relieve the pressure in the high pressure cylinder at some point below that at which a combustible mixture in the high pressure stage would be fired. This 85 thermostatic device may be rendered as sensitive as desired by forming the valve casing 14 and the valve stem 16 of relatively thin material so that they will respond almost instantly to temperature variations and if desired, the casing 14 may be insulated with any suitable heat insulating material as an asbestos covering 14' to prevent the radiation of heat from this valve member.

90 It will be noted that my thermostatic unloading means is composed of a very few parts which require a minimum amount of machining, that this mechanism may be applied to any compressor with a very slight 100 change in compressor construction, *i. e.*, the boring of a hole into the interior of the cylinder itself, and that the parts of the mechanism are easily assembled, adjusted, and repaired. It will further be noted that this 105 mechanism is positively operating, is not composed of any delicate parts, and may be very cheaply manufactured.

95 While I have in this application specifically described one embodiment which my invention may assume in practice, it is to be understood that this form is shown for illustrative purposes only, and that the invention may be modified and embodied in various other forms without departing from its spirit 110 or the scope of the appended claims.

115 What I claim as new and desire to secure by Letters Patent is:

1. In a compressor, in combination, a thermally operated unloading means comprising 120 a casing, a valve therein, operating means for said valve in said casing and comprising a plurality of members having different coefficients of heat expansion, and means for discharging pressure fluid from said casing 125 controlled by said valve.

2. In a compressor, in combination, a thermally operated unloading means comprising 130 a plurality of concentrically disposed members having different coefficients of heat ex-

- pansion, the outer one of said members constituting a casing, and means for continuously admitting the compressed medium between said members.
- 5 3. In a compressor, in combination, a thermally operated unloading means comprising a plurality of members having different coefficients of heat expansion, and a lost motion connection between two of said 10 members.
4. In a compressor, the combination with a compression chamber, of a thermally operated unloading means mounted adjacent one end of the compression chamber, and means 15 for maintaining a constant communication between said means and the interior of said chamber.
5. In a compressor, the combination with a compression chamber, of a thermally operated unloading means therefor comprising a relief valve operative directly to vent said chamber, and thermal controlling means for the latter disposed in constant communication with a portion of said chamber in which 25 the maximum heat of compression is produced.
6. In a compressor, the combination with a compression chamber, of thermally operated unloading means mounted adjacent each 30 end of the compression chamber and exposed directly to the maximum temperatures produced during compression.
7. In a compressor, the combination with a compression chamber, of unloading means 35 therefor comprising a relief valve operative when opened to permit the discharge of fluid at pressures less than normal compressor discharge pressure, and means for controlling the operation of said valve including 40 heat responsive means in constant communication with said compression chamber.
8. In a compressor, in combination, an unloading means including a member having one coefficient of heat expansion, a second 45 member having a different coefficient of heat expansion, a valve element connected to said first named member, and a second valve element connected to said second named member, one of said valve elements being 50 movable relative to the other element upon a change in temperature.
9. In a compressor, in combination, an unloading means including a member having one coefficient of heat expansion, a second 55 member therein having a different coefficient of heat expansion, a valve element connected to said first named member, and a second valve element connected to said second named member, one of said valve elements being 60 movable relative to the other element upon a change in temperature.
10. In a compressor, in combination, an unloading means including a member having one coefficient of heat expansion, a second 65 member having a different coefficient
- of heat expansion, a valve element connected to said first named member, and a second valve element connected to said second named member by a lost motion connection, one of said valve elements being movable 70 relative to the other element upon a change in temperature.
11. In a compressor, in combination, an unloading means including a member having one coefficient of heat expansion, a second 75 member having a different coefficient of heat expansion, a valve element connected to said first named member, and a second valve element connected to said second named member by an adjustable lost motion 80 connection, one of said valve elements being movable relative to the other element upon a change in temperature.
12. In a compressor, in combination, an unloading means including a member having one coefficient of heat expansion, a second 85 member having a different coefficient of heat expansion, a valve element connected to said first named member, and a second valve element connected to said second named member by an adjustable spring pressed lost motion connection, one of said valve elements being movable relative to the other element upon a change in temperature.
13. In a compressor, in combination, an unloading means including a member having one coefficient of heat expansion, a second 90 member having a different coefficient of heat expansion, a valve seat connected to said first named member, and a second valve element 95 connected to said second named member and adapted to coöperate with said seat, one of said valve elements being movable relative to the other element upon a change in temperature.
14. In a compressor, in combination, an unloading means including a member having one coefficient of heat expansion, a second 100 member having a different coefficient of heat expansion, a valve seat connected to said first named member, and a second valve element 105 connected to said second named member and adapted to coöperate with said seat, one of said valve elements being movable relative to the other element upon a change in temperature.
15. In a compressor, in combination, an unloading means including a member having one coefficient of heat expansion, a second 110 member therein spaced therefrom having a different coefficient of heat expansion, guiding means between said members, a seat on one of said members, a coöperating valve head on the other of said members, and 115 means for supplying fluid from said compressor to the space between said members, said valve head being moved from and toward said seat upon increase or decrease respectively in the temperature of said fluid. 120
- 60 65 70 75 80 85 90 95 100 105 110 115 120 125 130

16. In a compressor, in combination, an unloading means including a member having one coefficient of heat expansion, a second member therein spaced therefrom having a different coefficient of heat expansion, guiding means between said members, an adjustable lost motion connection between said members, a seat on one of said members, a coöperating valve head on the other of said members, and means for supplying fluid from said compressor to the space between said members, said valve head being moved from and toward said seat upon increase or decrease respectively in the temperature of said fluid.
17. In combination, a compressor, an unloading valve therefor, thermostatic controlling means for effecting opening of said valve on rise of temperature, and means for normally retaining said valve closed, said means being operative to prevent the application of more than a predetermined desired pressure on said valve when closed.

In testimony whereof I affix my signature.

HALBERT B. HALVORSEN.
